DESIGN FOR A MILK CAN

Stefan S. Starzec, Starzec, and Yelmer V. Sims,
Ladysmith, Wis.

Application May 26, 1939, Serial No. 85,220

Term of patent 14 years

To all whom it may concern:

Be it known that we, Stefan S. Starzec and Yelmer V. Sims, citizens of the United States, residing, respectively, at Starzec and Ladysmith, in the county of Rusk and State of Wisconsin, have invented a new, original, and ornamental Design for Milk Cans, of which the following is a specification, reference being had to the accompanying drawing, forming part thereof.

Figure 1 is a view in elevation of a milk can, embodying our new design; and

Figure 2 is a top plan view of the same, with the handle in section and a portion of the milk can shown broken away.

We claim:

The ornamental design for a milk can, as shown.

STEFAN S. STARZEC.
